[57] CLAIM

The ornamental design for a window component extrusion, as shown and described.

DESCRIPTION

FIG. 1 is a broken perspective of one side of the extrusion;

FIG. 2 is a corresponding broken perspective from the opposite side of the extrusion compared to FIG. 1;
FIG. 3 is a broken perspective of one side of a variant of the extrusion shown in FIG. 1, wherein the two small inwardly-facing ridges upon the left hand vertical wall are omitted; and

FIG. 4 is a corresponding broken perspective from the opposite side of the extrusion compared to FIG. 3.

FIG.1

FIG.2

FIG. 3

FIG. 4
